CIRCUIT CONTROLLER

Harry L. Lambert, Enfield, N. Y., assignor, by
mesne assignments, to Walter J. Pickering, New
York, N. Y.

Application June 26, 1943, Serial No. 492,395

13 Claims. (Cl. 200—80)

1

This invention relates to circuit controllers, and particularly to those which are responsive to centrifugal forces for their operation.

In my prior Patents No. 2,301,217, issued November 10, 1942, and No. 2,333,533, issued November 2, 1943, I have disclosed several forms of a mercury tube switch which may be employed to control a circuit selectively in accordance with centrifugal forces acting upon a globule or small body of mercury or other conducting liquid contained within a closed chamber. In all of said prior devices the circuit controlling action can only be adjusted by shifting the tube switch bodily to different distances from the axis about which it is bodily rotated in use.

An object of the invention is to improve the adjustment of mercury tube switches of the type that are responsive to centrifugal forces so as to cause them to operate at different speeds.

Another object of this invention is to provide an improved centrifugally operated circuit controller utilizing a mercury tube switch, with which any adjustment to operate at different speeds may be made in a simple manner, and with considerable accuracy.

Another object of the invention is to provide an improved speed control for an electric motor, with which the maximum allowed speed for the motor may be varied within substantial limits by simple adjustments.

Another object of the invention is to provide an improved, centrifugally operated circuit controller having simple and novel means for varying the speed of rotation at which it will open or close a circuit, which may be easily and quickly adjusted to vary the speed at which it becomes effective, and which will be relatively simple, compact, dependable, durable and inexpensive.

Another object of the invention is to provide an improved circuit controller which may be utilized to control a circuit at any of a plurality of selected speeds, with which the device may be made responsive to one speed or another by simple manipulations, with which the change in selected speed limits may be made without stopping the operation of the controller, and which will be relatively simple and inexpensive.

Another object of the invention is to provide an improved, centrifugally operated, mercury tube switch which may, by its mounting with respect to the axis of rotation, be caused to operate at different speeds of such rotation.

Other objects and advantages will be apparent from the following description of some embodi-

2

ments of the invention, and the novel features will be particularly pointed out hereinafter in connection with the appended claims.

In the accompanying drawings:

5 Fig. 1 is a side elevation of a circuit controller constructed in accordance with this invention and illustrating one embodiment thereof, a portion of the mechanism being broken away to show interior parts;

10 Fig. 2 is a transverse, sectional elevation of the same, the section being taken approximately along the line 2—2 of Fig. 1;

15 Fig. 3 is a longitudinal, sectional elevation through a mercury tube switch forming part of this controller, and of the type shown in Figs. 1 and 2;

20 Fig. 4 is a longitudinal, sectional elevation through another type of mercury tube switch that may be employed in the controller of Figs. 1 and 2.

25 Fig. 5 is a transverse, sectional elevation through the device of Fig. 4;

Fig. 6 is a longitudinal, sectional elevation of a normally open circuit type of mercury tube switch which may be also employed in the controller of Figs. 1 and 2;

30 Fig. 7 is an end elevation of the same;

Fig. 8 is a longitudinal, sectional elevation of still another type of mercury tube switch that may be employed in the circuit controller of Figs. 1 and 2;

35 Fig. 9 is an end elevation of the same;

Fig. 10 is a schematic wiring diagram showing a motor in series with and controlled by a circuit controller constructed in accordance with this invention and having three possible selections of maximum speeds;

40 Fig. 11 is a schematic diagram showing one possible circuit in which a small controller of the type shown in Figs. 1 to 4, 8 and 9 may be employed to control the speed of operation of a motor with quick change between two possible but variable maximums;

45 Fig. 12 is a similar diagram illustrating how a normally open circuit switch of the type shown in Figs. 6 and 7 may be employed in the controller mechanism of Figs. 1 and 2 to control the speed of operation of a motor at either of two possible selective speeds.

50 In the embodiment of the invention illustrated in Figs. 1 to 3, the controller is rotated by a shaft 1, which may be a motor shaft or any other rotatable element extending loosely through a block 2 of suitable insulating material. A plate 3 of insulating material is provided with a metallic sleeve having a collar 4 which telescopes over

and is secured upon the end of the shaft 1 in any suitable manner, such as by a set screw 5 passing through the collar 4 and engaging the shaft 1. The collar 4 spaces the plate 3 and the block 2, and upon the face of the plate 3 towards the block 2 are a plurality of concentric collector rings 6, 7 and 8 which may be countersunk to some extent into the face of the plate 3. These rings are secured to the plate for rotation therewith in any suitable manner, such as by studs 9 passing through the plate 3 and the collector rings. The studs 9 have shouldered, reduced ends which pass through apertures in the collector rings, with the free end beyond the ring upset, and the other ends of the studs 9 are also shouldered and reduced and have riveted thereon spring contact, metal arms 10. The collector rings on one face of the plate 3 and the contact arms 10 on the other face of the plate 3 prevent endwise movement of the studs 9 in the plates 3 and definitely anchor the collector rings 6 and 7 to the plate 3.

A pair of spring clamp arms 11 and 12 are disposed face to face, but spaced with relation to one another, with their corresponding ends parallel and connected by bolts 13. Between their ends, these arms 11 and 12 are made oppositely concave at corresponding zones of their adjacent faces so as to form between them a socket which receives the base 14 or body of a mercury tube switch. In this particular example, there are two of such sockets, one formed adjacent each end of the unit formed of the pair of arms 11 and 12, and each of which sockets mounts a mercury tube switch. These switches may also, for convenience, be distinguished from each other by the letters A and B. By tightening the bolts 13, the arms 11 and 12 can be brought together so as to frictionally and yieldingly clamp between them the mercury tube switches A and B. By loosening the bolts 13, the switches A and B may be individually rotated about their own axes in their sockets formed between the arms 11 and 12, and then clamped in different rotative positions by retightening of the bolts 13. The central portions of the arms 11 and 12 are provided with laterally extending lugs or flanges 15 which lie flat against the adjacent face of the plate 3, and the screws 16 pass through these flanges or lugs 15 and into studs 10a passing through the plate 3 and anchored to the central collector ring 8. The flanges or arms 15 serve in place of the contact arms 10 to prevent endwise movement of the studs 10a.

The switches A and B may be similar in construction, and in the particular example shown, each of these switches is provided with a generally spherical shell 17, see Fig. 3, which has an opening in one side and a short, outwardly extending flange 18 surrounding such opening. This casing 17 is made of conducting material not wet by mercury, such as a shell made of pure iron, or of selected alloys. A plate 19 of glass having a coefficient of expansion approximately equal to that of the metal of the casing 17 is placed across the opening of the casing 17 and fused to the flange 18 so as to close the casing 17. By closing this casing 17 with this glass closure plate 19, it is possible to exhaust the chamber 20 within the casing 17 of air and replace it with an inert gas, as usual in mercury tube switches.

A conductor 21 extends through the plate 19 of glass into the chamber 20, and within the chamber 20 it terminates in an exposed contact head 22 which is generally spherical, but smaller

in diameter than the chamber 20. This head 22 is eccentric to the wall of the chamber 20, as clearly shown in Fig. 3. In Fig. 3 the axis of head 22 is shown by the line 22a, and the axis of chamber 20 is shown by the line 20a. The portion of the conductor head 22 within the chamber 20 and the portion passing through plate 19 are also made of pure iron or any alloy or conducting material not wet by mercury and having approximately the same coefficient of expansion as the glass of plate 19. The conductor 21 extends some distance beyond the plate 19 and terminates in a head 23. Surrounding and telescoping over the periphery of the plate 19 is a metal sleeve or ferrule 24 which may be electrically connected to the casing 17 in any suitable manner, such as by solder or a small piece of welding 25. A disk 26 closes the outer end of this sleeve or ferrule 24 and is confined therein by the flange of the head 23 of the conductor. The chamber within the ferrule 24 is filled with a suitable insulating material 27, as usual in electric filament lamp bases.

Within the chamber 20 is disposed a globule or small body 28 of liquid mercury which, when the switch is idle and supported in the position shown in Fig. 3, will rest upon a side wall of the chamber 20 and touch the head 22. The globule or body of mercury 28 is of such size that it normally assumes a somewhat ball-like form in which a substantial portion thereof is held away from the wall against which it rests, or against which it is confined, by its surface tension acting in opposition to the forces of gravity upon the mercury.

It will be noted from Fig. 3 that the head 22 is much nearer one zone in the periphery of the side wall of the chamber 20 than it is at the directly opposite side, because the head 22 is eccentric to the chamber 20. The mercury 28 is normally sufficient in depth to touch the head 22 when in the widest portion in the space between the head 22 and the wall of the chamber 20, as shown in Fig. 3.

When a switch of the type shown in Fig. 3 is mounted between the arms 11 and 12, as shown in Figs. 1 and 2, the arms 11 and 12 will grip and clamp the sleeve or ferrule 24, which is electrically connected to the casing 17. When the switch is so mounted between the arms 11 and 12, the head 23 on the outer end of the conductor 21 will abut against one of the contact arms 10 and provide an electrical connection between the contact head 22 within the chamber 20 and a collector ring 55 on the plate 3. In the examples shown in Figs. 1 and 2, the head 23 of the conductor 21 of the switch A will engage with the arm 10 which is connected through a stud 9 to the collector ring 7, and the conductor head 23 of the switch B will engage the contact arm 10 that is connected through a stud 9 through the collector ring 6. The sleeves or ferrules 14 of both switches A and B will be connected through the arms 11 and 12, screw 16 and studs 10a to the collector ring 8.

A plurality of brushes 29, 30 and 31 are mounted in sockets in the block 2 and yieldingly urged outwardly by individual springs 32. Suitable circuit connection are made through the brushes 29, 30 and 31, so that the wire connected to the brush 29 will be connected through that brush to one of the collecting rings. The wire connected to the brush 30 will be connected through that brush to another collecting ring, and the wire connected through the brush 31 will be connected therethrough to another collecting ring. Any de-

sired number of mercury tube switches may be similarly mounted on the plate 3, with one terminal of each connected to a common collector ring, and the other terminal of each connected to an individual collector ring, as in the circuit diagram of Fig. 10.

In the diagram of Fig. 10, three of such switches A, B and C are similarly clamped or mounted in sockets on the plate 3, and each of these switches has a terminal thereof connected to the common collector ring which is connected through a brush to a circuit wire 33 of a circuit to be controlled. The other terminal of the switch A is connected through a brush to a circuit wire 34 which leads to a switch contact 35. The other terminal of the switch B is connected by a wire 36 to a switch contact 37, and the other terminal of the switch C is connected by a wire 38 to a switch contact 39.

These contacts 35, 37 and 39 are arranged in a suitable sequence so as to be engaged selectively one at a time by a contact or switch arm 40 adjustable about a pivot 41 and provided with an operating handle 42. The switch arm 40 is connected by a wire 43 to one line wire, such as L', the other line wire L² being connected to one side of a motor M. The other side of the motor M is connected to the wire 33, so that the motor M will be in series with one of the switches A, B and C, depending upon the position of the switch contact 40. Each of the switches A, B and C is individually rotated in its socket between arms 11 and 12 until the portion of the chamber 20 thereof which is farthest from the axis of rotation of the shaft 1 will be that which will cause separation of the mercury globule from the contact 22 at a desired speed, which speed will preferably and usually be different for each of the switches A, B, and C.

For example, the switch A may be set with the widest distance between the contact head 22 and the side wall of the chamber 20 farthest from the axis of the shaft 1, so that smaller centrifugal forces will be required to flatten the globule of mercury of that switch sufficiently to interrupt the current between the globule and the contact head 22. This may be designated as a "low speed." Similarly, the switch B may be set by rotating it through a partial revolution about its own axis to place the zone of the chamber 20 having a medium distance between the head and the chamber wall, farthest from the axis of rotation, which would be a "medium speed." The switch C may be set for high speed by rotating it through a partial revolution about its own axis and in its socket until the shortest distance between the head and the adjacent chamber wall is farthest from the axis, and larger centrifugal forces will then be required to flatten the globule thereof sufficiently to remove it from contact with the head 22. When the shaft 1 is rotated in this manner, all of the switches A, B and C will be rotated bodily about the same axis, and as the machine starts, each of the globules will be in contact with a spherical head 22 and with a casing 17, so that regardless of whether the switch handle 42 is set in the high, medium or low positions, a circuit for the motor will be closed through whichever switch A, B or C is connected through the switch arm 40 to the line wire L'.

In this example, the shaft 1 which mounts the plate 3 is, of course, either the armature shaft of the motor M or a shaft which is driven at a desired speed ratio therefrom. Let it be assumed, for example, that the switch handle 42 is set for a medium speed, as shown in Fig. 10. This will complete a circuit through the wire 36 to the

switch B and to the motor M. The motor will then operate and rotate the plate 3 with the switches A, B and C thereon. When the centrifugal forces acting on the mercury in the switch B are sufficient to flatten or distort the globule of mercury therein against its surface tension until it withdraws from the head 22, this will open the circuit to the motor, whereupon the speed of the motor will fall. Just as soon as the speed falls slightly, the surface tension of the globule of mercury in the switch B will partially restore to the globule its former form or shape and reestablish contact with the head 22 in the switch B, thus recompleting the circuit through the motor M. The circuit of the motor M will be automatically opened at the switch B as soon as the speed reaches a selected speed, and will be reclosed as soon as the speed falls slightly.

The motor will thus be automatically governed to run at a speed not exceeding this medium speed for which the switch B is set. While this is happening the mercury globules in the other switches A and C will similarly be flattened by centrifugal forces to vary extents, but since the circuits therethrough are not completed at switch arm 40, they will have no influence on the motor M at this time. When the switch arm 40 is shifted to either low or high position, it will place the switches A or C respectively in the circuit of motor M, and since those switches are set for different speeds, the circuit of the motor M will be opened whenever the speed exceeds that speed for which the switch in series with motor M is set by rotation about its own axis. Thus, while the motor M is running or while it is idle, one may shift the switch arm 40 to place the motor M under the control of any one of the mercury tube switches A, B or C. It will be understood, of course, that any desired number of switches may be mounted on the plate 3, and individually made effective by a selective switch.

In Figs. 4 and 5, the mercury tube switch is slightly different than that shown in Figs. 1 to 3, in that the housing or casing is made of a cylindrical sleeve 44 of pure iron or other metal not wet by mercury, which is closed at its ends by plates 45 and 46 of a glass having approximately the same coefficient of expansion as the material of which the sleeve 44 is made. A conductor 47 extends through one of these glass plates, such as 46, into the chamber 48 within the cylinder 44, and is received and supported in a recess 49 provided in the inner face of the other glass plate 45. The portion of the conductor 47 which passes through the plate 46 may be made of the same material as the cylinder 44, so as to have approximately the same coefficient of expansion of that of the glass of which plate 46 is made, and if desired, the portion within the chamber 48 may be made of a different metal not wet by mercury which is welded to the end of the conductor 47, as shown in Fig. 4. The globule or small body of liquid mercury 50 is disposed within the chamber 48 as in the switch shown in Figs. 1 to 3.

The conductor 47 is eccentric to the wall of the chamber 48, that is, to the cylinder 44, the axis of the conductor 47 being shown by the center line 51 and the axis of the chamber 48 being shown by the center line 52. Thus, the conductor 47 will be relatively nearer the wall of the chamber 48 at one side, and relatively farther at the diametrically opposite side of the chamber, and the distance from the conductor 47 to the zones of the peripheral wall of the chamber

48 between these two points will vary progressively. The cylinder 44 can be clamped between the arms 11 and 12 in place of the switches A and B and by such clamping it will be electrically connected to the arms 11 and 12 in the same manner that the casing 17 in Figs. 1 to 3 was, through the ferrule 14, electrically connected to the arms 11 and 12. The outer end of the conductor 47 will bear against a contact arm 10 in the same manner as in Figs. 1 to 3, so that the type of switch shown in Figs. 4 and 5 can be substituted for that shown in Figs. 1 to 3 and will function in a similar manner.

By rotating the cylinder or sleeve 44 in its socket between the arms 11 and 12 through a part of a revolution, one may set the switch to position any zone of the periphery of cylinder 44, against which the mercury may be confined by centrifugal forces farthest from the axis of the shaft 1. If at any time, such zone is that which has the greatest distance to the conductor, then two centrifugal forces necessary to flatten the globule and break contact between the globule and the center electrode or contact 47 will be less than when the mercury is confined by centrifugal forces in some other part of the chamber of the switch. Thus, one may, by merely rotating this switch in its socket, vary the speed at which the circuit therethrough will be opened.

In Figs. 6 and 7, the mercury tube switch is of the type shown in Figs. 1 and 2 of said Patent No. 2,301,217. In that type of switch, the housing or casing 53 is made generally elliptical in shape and of glass, but one end portion thereof is made reentrant in the form of a tubular post 54. The outer end of this post is closed by an element 55 of insulating material, which may complete the generally elliptical shape of the exterior of the housing 53. In this particular example, the post 54 may be disposed concentrically of the chamber 56 within the housing. A conductor 57 passes through the element 55 and along the interior of the post 54, approximately to the other end of the post, then it passes through the wall of the post into the chamber 56, where it terminates as a loop encircling the post but in spaced relation to the wall of the chamber and the periphery of the post 54. Similarly, a conductor 58 extends through the element 55 and the adjacent end of the housing 53 into the chamber 56, and there it terminates as a loop which encircles the post 54 at that end of the chamber and is largely in spaced relation to both the housing 53 and the post 54.

In this particular example, the planes of the two loops are made convergent in one direction, as shown in Fig. 6, and both equally distant from the center of any globule of liquid confined on the periphery of the chamber wall by centrifugal forces created by bodily rotation of the casing 53, so that the distance between loops at one side of the chamber 56 will be less than between the corresponding parts of the loops at the other side of the chamber 56. The distance between these loops will, of course, progressively vary in a direction peripherally of the chamber. A globule or small body 61 of mercury in liquid form is placed within the chamber 56 and its surface tension acting against the forces of gravity causes this mercury to form a somewhat ball-like form as shown in Fig. 6, in which a substantial portion of the mercury is held solely by its surface tension away from and against spreading along the wall of the chamber 56 on which it rests or against which it is confined by centrifugal

forces. When a switch of this type is mounted between the arms 11 and 12 in Figs. 1 to 3 in place of either of the switches A and B, the elliptical housing 53 will be clamped frictionally in the socket between the arms 11 and 12, so that it may be rotated individually in its socket, and about its longitudinal axis which will be the longitudinal axis of the chamber 56, so as to place any particular peripheral zone of the wall of chamber 56 farthest from the axis of the shaft 1.

When the shaft 1 is rotated, the mercury 61 will, of course, be moved by centrifugal forces into the zone of the chamber 56, which is farthest from the axis of rotation of the shaft 1, and it will be confined against that zone of the wall undivided and relatively immovable, as the shaft 1 continues its rotation. The mercury globule 61 normally is too short to contact both of the loops 59 and 60, but as the speed of rotation with the shaft 1 increases, the globule 61 will be flattened more and more, which causes it to increase its length along the chamber 56 until finally it will electrically connect the loops 59 and 60 and through them, the conductors 57 and 58. The speed and consequently the centrifugal forces which are required to flatten or distort the globule 61 until it electrically connects the loops 59 and 60 will vary with the distance between the loops 59 and 60 at the zone of the chamber 56 where the mercury globule happens to be confined by such rotation, or by the distance from the center of the globule and the loop which is farthest from the center of the globule. For example, if the housing 53 is so disposed that the zone of the chamber 56 having the shortest distance between the loops 59 and 60, is farthest from the axis of the shaft 1, then relatively low centrifugal forces will be required to flatten the globule 61 sufficiently to connect the loops 59 and 60, but if the globule is confined in the zone of the chamber 56, such as shown in Fig. 6, by the centrifugal forces, where the distance between the loops is the maximum, then a much higher speed will be required to create centrifugal forces high enough to elongate the globule of mercury to the extent necessary to connect the loops 59 and 60 at that side of the chamber 56. Obviously, the housing 53 may be rotated in its own socket about its own axis to place any other part of the chamber 56 farthest from the axis of shaft 1.

In Figs. 8 and 9, still another form of the switch is shown, in which the housing 62 is generally of cylindrical shape, but provided with a re-entrant end portion to form a hollow, internal post 63, which post, however, extends the full length of the chamber 64 and is eccentric thereto. A conductor 65 passes through one end of the housing into the chamber 64 and then is wound spirally around the post 63 to the other end of the chamber 64. A second conductor 66 also enters the chamber 64 and is similarly wound spirally about the post 63 in spaced relation to the conductor 65 to the opposite end of the chamber 64. Thus, the two conductors are wound spirally in spaced relation to each other on the periphery of the post 63 from one end of the chamber to the other. A globule or body 67 of mercury is provided in the chamber 64 as for the chambers of all of the other switches described herein, so that no matter what zone of the peripheral wall of the chamber of mercury may be confined against it, it will, by its shape, induced by surface tension, normally engage and

electrically connect the spaced turns of the conductors 65 and 66.

When the housing 62 is mounted between the arms 11 and 12 in Figs. 1 and 2 in place of the switches A and B, it may be turned about its own axis in the socket formed between the arms 11 and 12, so as to place farthest from the axis of the shaft 1 any desired peripheral zone of the chamber 64. For example, when the zone of the chamber 64 having the greatest distance from the post 63 to the outside wall is placed farthest from the axis, then smaller centrifugal forces will be required to flatten the globule of mercury sufficient to separate from one or both of the conductors 65 and 66 and open the circuit between them through the mercury. Thus, by rotating the housing 62 about its own axis in its mounting between arms 11 and 12, the speed at which the centrifugal forces will flatten the globule sufficiently to break the circuit between the conductors 65 and 66 may be varied.

It will be understood that in all forms of the switches, the circuits through the switches may be opened or closed depending upon the type of switch, at any selected speed, and the circuits through these switches may be signal circuits which operate suitable signals, or any other desired apparatus, or if they are included in series with the motor, or a relay controlling a motor, they may control the speed of the motor and prevent such motor from exceeding a selected speed, which speed may be varied by rotating the individual switch about its own axis.

In Fig. 11, I have shown diagrammatically the control of a motor 68 by either of two switches of the type shown in Figs. 1 to 3, which may be so selected or adjusted that the motor speed will not exceed the selected speed of either of two predetermined speeds. In this form of the invention, a relay is employed for controlling the motor circuit, so that a relatively large motor may be employed and its speed controlled by a relatively small capacity, mercury tube switch.

In this circuit, the line wire L' is connected to a contact 69 of a relay R and the moveable arm or contact 70 of that relay is connected by a wire 71 to one terminal of the motor 68. The other terminal of the motor 68 is connected by a wire 72 to the line wire L². The switch arm 70 of the relay is yieldingly urged into open circuit position by a spring 73. The winding 74 of the relay is connected at one side to the line wire L², and at its other side by a wire 75 to the brush which bears upon the collector ring 8; so that through that collector ring it will be connected to one terminal of each of the mercury tube switches A and B which are mounted on the plate 3. The plate 3, in this example, is shown as mounted directly on the shaft 1 of the motor 68, but it will be understood that the shaft 1 may be driven from the armature shaft of the motor 68 through a suitable speed changing mechanism, if desired. The central electrode of the switch A is connected through a brush and collector ring and a wire 76 to a contact 77 of a switch 78. The central electrode of the other switch B is connected through a brush and collector ring and a wire 79 to another contact 80 of the switch 78. The switch 80 has a contact arm 81 which may be shifted alternately between the contacts 77 and 80 so that circuits through the switches A and B may be made alternately available, depending upon whether a high or low speed control of the motor 68 is desired.

In this particular example, the switch A should

be rotated in its mounting until the selected peripheral wall zone of the chamber thereof is farthest from the axis of the shaft 1 to give the desired high maximum speed control. The switch B should be similarly turned in its socket until the selected peripheral zone of the chamber is farthest from the axis of the shaft 1 to give the desired low maximum speed control.

To operate such a system, the line wires L' and L² are connected to a suitable source of current, and the switch arm 81 is locked to place it in contact with the switch contact 77 when a low maximum speed is desired. When the motor is not operating, the mercury globule in the switch 15 A will complete a circuit through that switch and hence the movement of the switch arm 81 into engagement with contact 77 will complete a circuit through the switch A and the winding 74 of the relay R. This will attract the relay switch 79 and complete a circuit through the motor 68. The motor will start its rotation, and the mercury globules in each of the switches A and B will be thrown against the peripheral zone of the side wall of the chamber of that switch which is farthest from the axis of the shaft 1. As the speed of the motor increases, the mercury globules will be flattened to increasing extents, and when the globule in switch A flattens until it withdraws from the contact head 22 of that switch, this will open the circuit to the winding 74 of the relay, whereupon switch arm 79 of the relay is released and moved to open position. This opens the circuit of the motor and as the speed thereof falls, the mercury globule will be returned by its surface tension toward its former shape in engagement with the contact head 22 in that chamber and reestablish the circuit therethrough. This again energizes the winding 74 and recomplete the circuit to the motor 68. Thus, the speed of the motor will be kept below a maximum determined by the setting of the switch A in its individual socket or mounting.

When a higher maximum speed is permissible, the switch arm 81 is operated to engage the contact arm 80 which places the switch B instead of A in series with the relay winding and a similar control of the motor 68 is obtained, except that since the switch B is set to place farthest from the axis of shaft 1, the wall zone of the switch chamber which causes the globule to open the circuit through that switch at a selected maximum speed. Hence, a higher speed may now be obtained by the motor 68 before the globule in that switch B will be flattened sufficiently to leave contact with the head 22 of that switch and open the circuit of relay winding 74.

A somewhat similar circuit arrangement is shown in Fig. 12, but the winding 82 of the relay S acts upon a switch arm 83 which is urged into closed position against relay contact 84 by a spring 85. Another difference is that the switches D and E are of the normally open circuit type, such as shown in Figs. 6 and 7. The wire 76 in this instance will be connected to the switch E, and the wire 79 will be connected to the switch D. With such an arrangement to start the motor, the line wires L' and L² are connected to a source of current, and immediately a circuit is established through the relay switch arm 83 to the motor 68. At this time, the globule of mercury in each of the switches D and E will be out of contact with the loops 59 and 60 so that the relay winding 82 will be deenergized. The switch arm 81 is shifted, however, into engagement with one of the contacts 77 or 80, depending

upon whether the low maximum speed or high maximum speed is desired.

Assuming that arm 81 engages contact 77, this will establish a circuit from the winding 82 of the relay through the switch E. As the speed of the motor increases, the increasing centrifugal forces will flatten the globules 61 of the mercury of both switches E and E to greater and greater extents until globule 61 in switch E engages and connects the loops 59 and 60 of that switch when the desired maximum speed has been reached. This will complete a circuit through the winding 82 and the latter will move its switch arm 83 into open circuit position, thus opening the circuit to the motor 68. The speed of the motor then falls and the reduced centrifugal forces then acting on the globule 61 of switch E will be overcome by surface tension of the globule so as to partially restore the former shape of the globule and open the circuit between the loops 59 and 60. This de-energizes relay winding 82, and spring 85 then moves relay switch arm 83 back into closed circuit position. The motor will then again receive power and tend to build up its speed, but at no time can the speed of the motor increase above the speed for which the switch E is set. By shifting the switch arm 81 to engage contact 83, the switch D is made effective in place of the switch E, and thus a higher speed must be reached before the relay switch 83 will be opened to prevent further increase in the speed of the motor. The switches D and 3 are, of course, individually rotatable in their individual mountings so as to set them for the desired maximum speed at which the circuit therethrough is to be closed.

While mercury is the preferred conducting liquid for the globule or electrically conducting liquid because of its relatively high surface tension, any other electrically conducting liquid with substantial surface tensions is to be considered the broad equivalent of mercury, but when other liquids are employed in place of mercury, the chamber wall and the exposed electrode within the chamber should be of materials not wet by the liquid used. Other conducting liquids are usually less desirable because they may be subject to electrolytic decomposition by the electric current passing therethrough. The chambers of each housing or casing, after introduction therein of the conducting liquid or mercury, are exhausted of air and the air replaced with an inert gas to increase the effective life of the switches. This is easily done as usual with mercury tube switches, and the use of glass in closing the chambers makes easily possible this exhaustion of air and replacement of the air with another gas.

It is believed that the operation and use of the devices which have been illustrated and described will be clear from the foregoing description, but it will be understood that any of the mercury tube switches shown in Figs. 4, 5, 8 and 9 may be used as the switches A and B instead of the type shown in Fig. 3.

It will also be understood that various changes in the details, materials and arrangements of parts, which have been herein described and illustrated in order to explain the nature of the invention, may be made by those skilled in the art within the principle and scope of the invention as expressed in the appended claims.

I claim as my invention:

1. A circuit controller comprising a hollow housing having a closed chamber with a wall not wet by mercury, a body of mercury within and only partially filling said chamber, resting upon

a side wall thereof and of a size to assume a curved form in which a substantial portion thereof is held away from and against spreading along said wall, solely by its surface tension opposing the action of gravity thereon, a conductor extending into said chamber and therein having a contact with an exposed surface area not wet by mercury, eccentric to a transverse periphery of said chamber and spaced from and so disposed relatively to said chamber wall than when said housing is rotated bodily about an axis normal to the plane of said transverse periphery and eccentric to the axis of said chamber, said mercury will be held by centrifugal forces relatively immovable and undivided against the zone of said wall farthest from said axis of rotation and electrically connected to and disconnected from said contact area as it is distorted in shape by varying centrifugal forces, and a circuit connection to said mercury whereby rotary adjustment of said housing about its own axis to place different wall zones thereof farthest from its axis of bodily rotation, will vary the speed of said bodily rotation at which said electrical connection or disconnection is made.

2. A circuit controller comprising a hollow housing having a closed chamber with a wall not wet by mercury, a rotatable element, a support carried by said element and mounting said housing eccentrically of the axis of rotation of said element for rotation with said element, said housing being separately rotatable, about its own axis, on said support, a body of mercury within and only partially filling said chamber, resting upon a side wall thereof and of a size to assume a curved form in which a substantial portion thereof is held away from and against spreading along said wall, solely by its surface tension opposing gravity, a conductor extending into said chamber and having therein a contact with an exposed surface area not wet by mercury, eccentric to said housing axis, and spaced from said chamber wall whereby when said housing is rotated with said element, said mercury will be confined by centrifugal forces, undivided and relatively immovable against the zone of said wall farthest from the axis of said element and electrically connected to and disconnected from said contact area as its shape is varied by the opposing centrifugal forces and surface tension, and a circuit connection to said mercury whereby the speed at which an electrical connection or disconnection is made between said contact area and said mercury may be varied by adjustment of said housing about its own axis on said support.

3. A circuit controller comprising a rotatable element, supporting means carried by and rotatable bodily with said element, a hollow housing mounted by said supporting means eccentrically to the axis of rotation of said element, additionally rotatable about its own axis in said supporting means and having a closed chamber with a wall not wet by mercury, a globule of mercury within and only partially filling said chamber and of a size tending to assume a generally ball-like form, when resting upon a side wall thereof, solely by action of its surface tension in opposition to gravity, a conductor extending into said chamber and therein having a contact with an exposed surface area not wet by mercury and so disposed eccentrically with respect to said chamber, and in contact with said globule while said globule is confined, undivided and relatively immovable, against a zone of said wall by centrifugal forces created by bodily rotation of said housing

with said element, from which said globule may separate as said globule undergoes changes in shape under the opposing forces of surface tension and the centrifugal forces due to its bodily rotation, and circuit connections to said globule and conductor whereby the centrifugal forces necessary to produce engagement or separation of said globule and contact will vary with rotation of said housing about its own axis to vary the wall zone against which the globule is confined by the centrifugal forces created by the bodily rotation of that housing.

4. A circuit controller comprising a hollow housing having a closed chamber with a wall not wet by mercury, a globule of mercury within and only partially filling said chamber, resting upon a side wall thereof and of a size to assume a generally ball-like form solely by its surface tension acting against gravity, a conductor extending into said chamber and therein having a contact with an exposed surface area not wet by mercury, located with respect to said globule while the latter is confined undivided and relatively immovable against a zone of said wall by centrifugal forces as said housing is rotated bodily about an axis eccentric to the axis of said chamber, in a position to engage with and be separated from said globule as said globule changes shape under the opposing forces of surface tension and centrifugal forces due to its bodily rotation, and a circuit connection to said globule, said contact being disposed at different distances from different zones of the periphery of said wall whereby when said globule is confined in different zones around the periphery of said wall by said centrifugal forces, the speed of said bodily rotation of said housing which will produce engagement or separation of said globule and contact will vary with the wall zone against which the globule is confined by the centrifugal forces set up.

5. The controller substantially as set forth in claim 4, and a rotatable element, and a support rotating with said element and mounting said housing for selective increments of rotation about said chamber axis to place different zones of said chamber side wall farthest from the axis of rotation of said element.

6. A circuit controller comprising a hollow housing having a closed chamber with a wall not wet by mercury, a small body of mercury within and only partially filling said chamber and of a size to assume a curved form in which a substantial portion thereof is held above and against spreading along, said wall solely by its surface tension opposing the action of gravity thereon, a conductor extending into said chamber from the exterior of said housing and within said chamber having an exposed contact area disposed to be engaged by said mercury body or separated therefrom by changes in shape of said body under the opposing forces of said surface tension and the centrifugal forces acting upon said body when said housing is rotated about an axis eccentric thereto, said contact area having portions thereof disposed at different relative distances from the center of said mercury body while the latter is confined against different peripheral zones of said wall by centrifugal forces of said rotation, whereby by confining the mercury body, undivided and relatively immovable against different zones of said chamber around the periphery thereof, the centrifugal forces necessary to cause engagement or disengagement between said mercury body and contact area may be varied, and means for connecting said mercury

body and conductor in series with each other in part of a circuit to be controlled by the engagement or separation of said body and contact area.

7. The controller substantially as set forth in claim 6, and a support for said housing, in which said housing may be turned about its own axis, and an element mounting said support for rotation about an axis eccentric to said housing axis, whereby the housing may be rotated bodily about the axis of rotation of said element and also additionally rotated about its own axis to place different zones along the periphery of said wall farthest from said axis of rotation of said element.

8. A mercury tube switch comprising a hollow housing having a closed chamber containing an inert gas and with a wall not wet by mercury, a conductor extending into said chamber and having therein a contact with an exposed surface area substantially eccentric to, and spaced from, said wall, a globule of mercury within and only partially filling said chamber and of a size to assume a generally ball-like form solely by its surface tension acting against gravity, the distance from each zone of said wall to said contact being less than the thickness of said globule when the globule is resting on said zone, and circuit connections leading to said globule and said conductor, whereby when said housing is rotated about an axis eccentric to said chamber, the centrifugal forces created by such rotation will confine said globule against a zone of said wall, and flatten the globule an amount dependent upon the speed of rotation of said housing, the distance between the contact and the zone of the wall against which the globule is confined by centrifugal forces determining the speed at which the globule separates from said contact.

9. A mercury tube switch comprising a hollow housing having a closed chamber containing an inert gas and with a wall not wet by mercury, a contact in said chamber having an exposed surface area disposed at a plurality of different distances from different zones of the periphery of said wall at the intersection of said wall by a plane transverse to said chamber and approximately normal to said wall, a globule of mercury within and only partially filling said chamber and of a size to assume a generally ball-like form solely by its surface tension acting against gravity, the distance from different zones of said wall periphery to said contact surface area varying, whereby when said housing is rotated about an axis normal to said plane and eccentric to said chamber, said globule will be confined against 55 that one of the zones of said wall which is furthest from the rotation axis, and variably distorted with changes in centrifugal forces as the speed of rotation varies, said globule by its distortion engaging with and separating from said contact, and circuit connections to said globule and said conductor.

10. A mercury tube switch comprising a hollow housing having a closed chamber containing an inert gas and with a wall not wet by mercury, a contact in said chamber having an exposed surface area disposed at a plurality of different distances from different zones of the periphery of said wall at the intersection of said wall by a plane transverse to said chamber and approximately normal to said wall, a globule of mercury within and only partially filling said chamber and of a size to assume a generally ball-like form solely by its surface tension acting against gravity, the distance from different zones of said wall periphery to said contact surface area varying, a

support for said housing in which said housing may be adjusted angularly about an axis of said chamber normal to said plane, whereby when said housing and support are bodily rotated about an axis parallel to but offset from said chamber axis, said globule will be confined on a zone of said wall periphery which is furthest from said axis of rotation, and as the speed of rotation varies, opposing centrifugal forces and surface tension of said globule will distort said globule and cause separation and engagement of said globule and contact at selected speeds, which varies with the distance to said contact from said peripheral wall zone against which the globule is then confined, and circuit connections to said globule and said conductor from outside said housing.

11. A mercury tube switch comprising a hollow housing having a closed chamber containing an inert gas and with a wall not wet by mercury, said wall being circular in the transverse cross section formed by a plane containing a radius of curvature of said wall, a contact within said chamber and substantially eccentric to said center of curvature not spaced from said wall, a globule of mercury within and only partially filling said chamber, and of a size to normally assume a generally ball-like form solely by its surface tension acting against gravity, and circuit connections leading to said globule and said contact from the exterior of said housing, whereby when said housing is rotated about an axis parallel to, but offset from the axis of said chamber passing through the center of curvature of said cross section of said wall, said globule will be confined against said wall at said section in engagement with said contact, and as the speed of rotation increases, said globule will be flattened against said wall to increasing extents until it separates from said contact.

12. A circuit controller comprising a hollow housing with a closed chamber containing an inert gas and a wall not wet by mercury, said wall being a closed surface of generation about an axis of said chamber, a body of mercury within and only partially filling said chamber and of a size to normally hold a substantial portion of it, by the action of its surface tension alone in opposition to gravity, in curved form and away from the zone of said wall on which it may be resting, a conductor within said chamber in a position to be engaged by and separated from said body of

mercury as said body is confined against the portion of said wall furthest from said chamber axis when said housing is rotated about an axis parallel to but offset from said chamber axis, and flattened against said wall and released to different extents by varying centrifugal forces acting on said body and created by its rotation about said parallel and offset axis, said conductor being disposed at different distances from the center of said body as said body is confined against different peripheral zones of said portion of said wall which is furthest from said chamber axis, whereby the speed of rotation at which engagement and disengagement of said body and conductor occurs may be varied by disposing of said different wall zones furthest from said axis of rotation and connections to said body and said conductor from the exterior of said housing.

13. A mercury tube switch comprising a hollow housing having a closed chamber containing an inert gas and a wall not wet by mercury, said wall being circular in transverse cross section, a surface of generation, and arcuate in the generating line intermediate of its ends, a contact within said chamber, extending oblique to the axis of generation and disposed in spaced relation along said generation axis from the zone of said wall furthest from that axis, a body of mercury within and only partially filling said chamber, confined undivided and relatively immovably on a zone of said wall furthest from said generation axis when said housing is rotated about another axis parallel to and offset from said generation axis, and of a size such that its surface tension acting against gravity holds it in a curved form with a substantial portion away from said wall zone, whereby the centrifugal forces acting on said body, by reason of said rotation, in opposition to the surface tension of said body will distort said body and elongate it in a direction generally parallel to said generation axis, said contact being positioned along said generation axis for engagement by and separation from said body as the distortion of the body varies at selected speeds, which speed at which said engagement or separation occurs will vary with the zone of said wall against which said body is confined, and circuit connections to said body and said contact from the exterior of said housing.
